UNITED STATES PATENT OFFICE.

JAMES A. DUNNING, OF AULANDER, NORTH CAROLINA.

BRICKMAKING-MACHINE.

1,025,133.

Specification of Letters Patent.

Patented May 7, 1912.

Application filed July 12, 1909. Serial No. 507,226.

To all whom it may concern:

Be it known that I, JAMES A. DUNNING, a citizen of the United States, resident of Aulander, in the county of Bertie and State 5 of North Carolina, have made a certain new and useful Invention in Brickmaking Machines, and declare the following to be a full, clear, and exact description of the same, such as will enable others skilled in 10 the art to which it appertains to make and use the invention, reference being had to the accompanying drawings, and to letters or figures of reference marked thereon, which form a part of this specification.

15 Figure 1 is a central section of the invention, as applied. Fig. 2 is a detail perspective view of the die. Fig. 3 is a rear view of the same. Fig. 4 is a central section of the same on a larger scale. Fig. 5 is a similar 20 view of the central portion of the die on a still larger scale. Fig. 6 is a front view of the invention as applied to a machine for forming hollow cylinder products, showing the cylinder product as emerging therefrom. Fig. 7 is a central section of the 25 same. Fig. 8 is a rear view of the die for the same. Fig. 9 is a rear view of the die for forming tubular products of square cross section. Fig. 10 is a central section 30 of the same. Fig. 11 is a detail perspective view of the core-piece die for the same.

This invention has relation to brick, tile, hollow-block, pipe and other machines for forming plastic material into special shapes 35 by forcing the material, such as wet clay, sand and lime, sand and cement, or other moist plastic material through an orifice or die, and having for its object the improvement of said die.

40 The particular cause of inefficiency common to such machines is the inequality of flow of the mass of plastic material in its passage through the die, resulting from the unequal friction lengthwise the direction of 45 flow, in machines furnishing a rectangular or polygonal column of material, and depending in degree upon the departure in shape from the circular form, and similarly affecting both inner and outer surfaces of 50 a tubular column of plastic material; while transversely of the direction of flow there

is likewise inequality of flow in the mass of material, in all cases, by reason of the friction between the surfaces of the moving plastic material and the stationary die, the 55 part of the emerging column against which least frictional resistance is exerted being farthest removed from the contacting surfaces of the die and the plastic material. Because of these inequalities of flow the 60 less plastic clays or other less tenacious materials are not successfully worked inasmuch as they require a larger proportion of water in the mass to render them sufficiently plastic, such addition of water rendering 65 them too soft and tender to withstand the frictional inequalities before mentioned, so that the material passes through the die imperfectly formed; while even the extremely plastic materials have to be worked exces- 70 sively stiff to obtain complete and continuous conformation to the shape of the die, thereby requiring much more power to operate and resulting in greater lamination of product by reason of lack of sufficient mois- 75 ture in the material to secure an efficient binding of the particles. The resulting products from such die machines as are in general use are of unequal density and generally inferior in relation to quality, lami- 80 nation and early disintegration; excessive loss from breakage both while passing through the various stages of manufacture and after the product is finished being especially common. Yet excepting these dis- 85 advantages, for economy of manufacture and facility of producing various desired shapes, the column forming die machine is believed to possess superior advantages.

In the accompanying drawings, illustrating the invention, the letter *a* designates the throat of a brick making machine having converging side walls *a'*, *a'*, the feed device *b*, and the plate die *c*. This die is, with the object of overcoming the disadvan- 90 tages before stated, provided with an opening having converging side walls *c'*, *c'*, in line with and forming continuations of the side walls of said throat, said die having 95 also an inward extending endless marginal lip surrounding the opening of the die and having inner walls *d'*, *d'*, of a convergence 100

greater than the convergence of said side walls of the die opening and having an endless concave wall juncture *d'*, therewith gradually merging thereinto, this lip being 5 located at the line of emergence and having its greatest inward extension and its greatest compressive action upon the material being worked at the marginal or final point or line of contact. The depth or comparative prominence of this lip in forms of 10 rectangular or polygonal cross-section should be greatest at corners as at *e*, and less at points farthest removed from corners as at *f*, while in forms of circular cross-section it 15 should be of the same degree of prominence around the entire circumference, as indicated in Fig. 8 of the drawings. For cylindrical tubular forms the core *g*, for forming the inner tubular surface, as shown in Figs. 20 7 and 8 of the drawings, is likewise provided with a corresponding beveled or concave lip *h*, having contact with the inner surface of the column of material, and exerting its greatest compressive action at the final 25 point of contact.

While the ordinary form of die accomplishes compression by means of converging surfaces, the further final sharper convergence of such surfaces at the point of emergence as provided for by the means stated 30 is found in practice to give superior results in that it enables wetter and tenderer grades of material as well as the more plastic to be successfully worked, increases the 35 rate of production and requires less power.

For products of rectangular or polygonal cross-section, as shown, an outward extension *f*, is designed to be provided for each side of the die, such extension being of 40 segmental form and being extended outward farther in proportion the nearer the sides of the die approach the center, the arcuate margin or boundary of such extension extending from corner to corner of the die. 45 The concave lip in such cases of course conforms to the marginal arc but is designed to be, for perfection of work, slightly more extended in depth or prominence at the corners, gradually diminishing toward the center as hereinbefore indicated, thereby providing 50 greater compression of the plastic material immediately at the angular portions thereof, while at the same time releasing such angular portions before releasing 55 the corresponding transverse portions of the column. The greater depth or prominence of the lip at the corners of the die also compensates for the concavity that would otherwise be produced by such extension of the 60 die. It is found in practice that the width of such extension should approximate a distance equal to one third of its length or distance from corner to corner. For tubular

forms other than circular, the core for forming the inner surface is likewise provided 65 with corresponding extensions and beveled or preferably concave lips, as shown in Figs. 9, 10, and 11 of the drawings.

Having thus described my invention, what I claim as new and desire to secure by Letters Patent is:—

1. A die for shaping the product of a column forming machine for working clay and the like, consisting of a plate having an aperture provided with converging side 75 walls and an inward extending endless marginal lip of comparatively slight extent entirely surrounding said aperture and having concave walls of a comparatively sharp convergence greater than that of the side 80 walls of said aperture and gradually merging thereinto and acting to finally and sharply compress the product of the machine just before it emerges from the die.

2. In a column forming machine for 85 working clay and the like, having uninterrupted continuously converging clay compressing walls, a die consisting of a plate having an aperture provided with converging side walls in line with and forming continuations of the clay compressing walls of 90 the machine, and an inward extending endless marginal lip of comparative slight extent and prominence entirely surrounding said aperture and having concave walls of 95 comparatively sharp convergence, greater than that of the side walls of said aperture and merging thereinto, said lip acting to finally and sharply compress the product of the machine to a slight extent just before it 100 emerges from the die.

3.. A die for shaping the product of a column forming machine for working clay and the like, consisting of a plate having a polygonal aperture provided with converging 105 side walls and segment-shaped extensions provided with converging walls in line with and forming continuations of the side walls of said aperture, and an inward extending endless marginal lip entirely surrounding said aperture, said lip having inner walls of a convergence greater than that of the walls of said aperture and being of greater depth and prominence and having an increased inward projection from the 110 centers of said segmental extensions toward the corners of said aperture.

4. A die for shaping the product of a column-forming machine for working clay and the like, consisting of a plate having a polygonal opening having converging side walls and segment-shaped extensions corresponding to the sides of said opening and provided with converging walls in line with and forming continuations of said side walls 125 of the opening, and an inward projecting

endless marginal lip entirely surrounding the opening of the die, said lip having inner walls of a convergence greater than that of said converging walls of the segmental extensions and having an endless concave-wall juncture therewith gradually merging thereinto, said lip being of greater depth and prominence and having an increased inward projection from the center of the seg-

mental extensions toward the corners of the 10 die opening.

In testimony whereof I affix my signature, in presence of two witnesses.

JAMES A. DUNNING.
